UNITED STATES PATENT OFFICE.

CHARLES G. SCHMIDT, OF CINCINNATI, OHIO.

SWITCH FOR OVERHEAD-TROLLEY TRACKS.

SPECIFICATION forming part of Letters Patent No. 530,661, dated December 11, 1894.

Application filed August 13, 1894. Serial No. 520,108. (No model.)

To all whom it may concern:

Be it known that I, CHARLES G. SCHMIDT, a citizen of the United States, and a resident of Cincinnati, Hamilton county, State of Ohio, have invented certain new and useful Improvements in Switches for Overhead-Trolley Tracks; and I do declare the following to be a clear, full, and exact description of the invention, such as will enable others skilled in the art to which it appertains to make and use the same, attention being called to the accompanying drawings, with the reference numerals marked thereon, which form a part of this specification.

This invention relates to improvements in switches for overhead carrier-tracks for trolleys, such as are used in slaughter- and packing-houses, cooling-rooms, ware-rooms and factories, for the purpose of moving sides of beef, or other objects, quickly and conveniently from one place to another. The objects so moved are generally supported on hooks depending from rollers or trolleys which move upon the tracks. The latter are supported on brackets which depend from the ceiling. Switches in such track-systems are required to enable the convenient distribution of the objects, the meats for instance, into the different compartments, of the cooling-rooms, the annexes of main-buildings, &c.

This invention consists of a construction whereby the swinging end of the switch is supported in all its positions, even if not in alignment with the track ends, whereby it is prevented from breaking down in case a loaded trolley should accidentally enter upon it.

The invention embraces further the provision, construction and manner of supporting, of track-guards, operatively connected to the switch, whereby the open track-end is closed to the passage of trolleys, to prevent them from rolling off in case the switch has inadvertently been placed in the wrong position.

Other features are a reversible hanger, the means for locking the switch in position after alignment, and the details of the general construction.

In the following specification, and particularly pointed out in the claims, is found a full description of my invention, its operation, parts, and construction, the latter being also

illustrated in the accompanying drawings, in which—

Figure 1, is a perspective view of a switch 55 with parts of the adjoining tracks and showing the different features of my invention. Fig. 2, is an end-elevation, partly in section and looking from the switch toward the ends of the branch-tracks. Fig. 3, is a top view 60 of all the parts, obtained by a section on a line which passes between the tracks and the ceiling from which they are suspended. The other position of the switch is shown in all the views by dotted lines. 65

6, is the end of a main-track and 7, 8 are the ends of branch tracks, supported by hangers 9, 10, which are secured to the ceiling. Additional hangers (not shown) of similar construction, are provided at proper intervals to support the tracks through their entire length. 70

11 is the switch hinged at 12, to the end of track 6, and whereby the latter may be connected with either one of tracks 7 or 8. 75

13 is one of the trolleys, being substantially a roller, provided with a bracket 14 which carries the objects to be transported.

The lower part of the hangers is bent side-wise to bring the support for the track-ends 80 sufficiently inwardly, respectively away from the upper part of the hanger to permit the traveling trolleys to pass. This inwardly bent portion of the hanger on which rest the track-ends, is also extended longitudinally— 85 that is in line with the track and toward the switch, which extension forms a bracket 15, on which the swinging switch end rests while in alignment with the track. This extended bracket is also duplicated on the other side of 90 the hanger where it extends in opposite direction—that is, toward the track, whereby a more extended support is obtained for the latter and whereby, by a simple reversal of their position these hangers may be put up on 95 either side of the tracks to clear the brackets depending from the trolleys, which travel either all on one, or the other side of the tracks and whereby such hangers become available on either kind of trolley-system, requiring no 100

right or left hand hangers, to suit the contingency of trolley-travel. These brackets are provided with vertical flanges 16, to which the ends of tracks 7 and 8 are rigidly secured

and against which the switch-end rests when in position.

The switch is provided with an arm 17, rigidly connected and projecting laterally therefrom, from which a handle 18 depends, whereby the switch is operated from below. This arm is so located as to rest in all positions of the switch on brackets 15, respectively flanges 16 thereof, whereby the switch-end is supported, even if not resting on either one of brackets 15. Notches 19 are provided in the lower edge of arm 17, and properly located and distanced thereon, so that one or the two always engage with flanges 16, whereby the switch is held in position on either one of the brackets 15 and its lateral displacement prevented. By reason of this mode of locking, the operation of the switch requires a combined action. First it must be sufficiently lifted to disengage arm 17 from flanges 16, after which the lateral motion takes place to move the switch in line with either one of the track-ends. During this latter motion arm 17 slides on one of the flanges 16 and it drops down as soon as notches 19 reach said flanges, whereby the proper alignment is indicated and obtained. A stop 21 forms also a limit to the lateral motion of the switch in case the latter should have been lifted so high as to prevent the proper engagement of the notches with flanges 16.

To permit the first part of the operation, the lifting of the switch, its rear end is cut away slantingly as shown at 20.

For guarding the open end of either one of the tracks 7 and 8, while the switch is in alignment with the other end and to prevent trolleys from running off in case inadvertently moving thereon, I provide guards 22, and 23, carried by a guide-bar 24, which is supported and moves in slots 25, provided in the upper part of the hangers. The latter thereby form a rigid support for these guards and enable them to more completely withstand the impact of an approaching trolley. The guards are operated by means of an upright 26, carried by arm 17 and entering loosely into guide-bar 24, whereby the latter shares all lateral movements of the switch. The guards are so located on the guide bar that one is always over the open track-end, while the switch is aligned with the other track-end. The opening 27, in guide bar 24, into which upright 26 enters, is preferably elongated vertically, to permit the vertical movement or lifting of the switch when the same is operated.

As will be observed, arm 17, in its function as a switch-support, in cases where the switch has failed to reach its proper position, is materially aided by its connection to guide-bar 24, through upright 26, whereby all these parts form a well supported frame, consisting of members 17, 26 and 24, whereby the outer end of arm 17 is held down and more completely enabled to counteract the weight of a loaded trolley in case such should have entered upon the otherwise unsupported switch. The lat-

ter may be used without the guards where their use is not required and handle 18 may also be omitted where the switches are sufficiently low to be reached otherwise.

Having described my invention, I claim as new—

1. In a switch for overhead trolley-tracks, the combination of the branch-tracks 7, 8, 75 the hangers supporting them,—provided with brackets 15, and flanges 16, the switch 11 hinged to the main-track in a manner to permit a limited vertical movement in addition to its lateral swing, and an arm 17 rigidly secured to the switch, said arm provided with notches 19 in its lower edge and so located as to be in all positions above flanges 16, to enable notches 19, which are properly located, to engage with them for the purpose of locking the switch in position.

2. In a switch for overhead trolley-tracks, the combination of the switch 11, hinged to the main-track, the branch-tracks 7 and 8, the hangers supporting them, each provided 90 with a support for the free swinging end of the switch to rest on when in alignment with either track, a guide-bar 24, guided and supported by and on these hangers, which support the switch- and track-ends, guards 22, 95 and 23, carried by the guide-bar and an operative connection between this latter and the switch.

3. In a switch for overhead trolley-tracks, the combination of the branch-tracks, 7, 8, 100 the hangers supporting them, the switch 11 hinged to the main track, arm 17 rigidly secured to the switch, guards 22 and 23, to close the open track-ends, a guide-bar 24, guided by and on the hangers, and which 105 guide bar carries the guards and an operative connection between arm 17 and the guide-bar, whereby the latter is caused to move with the switch.

4. In a switch for overhead trolley-tracks, 110 the combination of the branch-tracks 7, 8, the hangers supporting them, provided with brackets 15 and flanges 16, the switch 11, hinged to the main-track in a manner to permit a limited vertical movement in addition 115 to its lateral swing, guards 22 and 23, to close the open-track ends, a guide-bar 24, guided by and on the hangers and carrying the guards, an arm 17 rigidly secured to the switch, and provided with notches 19 in its 120 lower edge and so located as to be in all positions above flanges 16, to enable notches 19 to engage with said flanges for the purpose of locking the switch, as well as the guards in position, an operative connection between 125 arm 17 and the guide-bar whereby the latter is caused to move with the switch and a handle to operate the latter from below.

5. In a switch for overhead trolley-tracks, 130 the combination of the branch-tracks 7, 8, the hangers supporting them, provided with brackets 15, the switch 11 hinged to the main-track, arm 17 rigidly secured to the switch and so located thereon as to be in all posi-

tions of the switch above brackets 15, to support the switch-end in all its positions and during its operation, a handle 18 on arm 17 for the purpose of operating the switch from below, the guide-bar 24 moving in slots in the upper part of the hangers, and upright 26 which connects the guide bar to arm 17, whereby these three members form a frame 24, 26 and 17, to aid arm 17 in its function 5 as a support for the switch in case the latter has missed its proper position.

6. A hanger for overhead trolley-tracks, provided with the upper horizontal part whereby it is secured in position, the vertical 15 depending part which carries the support for the track-end and is bent inwardly at its lower end to bring the track sufficiently to one side to permit the trolleys to pass the vertical

part of the hanger, said track-support being extended longitudinally, that is in the direction of the track and toward the switch to form a bracket 15 for the swinging end of the former to rest on, a flange 16 on said bracket to prevent the switch-end from passing beyond it, and a corresponding bracket and flange on the other side of the hanger, whereby 20 said hanger becomes adapted to be put up on either side of the track to clear the depending brackets of the trolleys, no matter 25 on what side of the track they travel.

In testimony whereof I affix my signature in presence of two witnesses.

CHARLES G. SCHMIDT.
